(57) **CLAIM**

What is claimed is the ornamental design for a battery pack, as shown and described.

DESCRIPTION

FIG. 1 is a first perspective view of a battery pack showing our new design;

FIG. 2 is a right side elevational view thereof;

FIG. 3 is a left side elevational view thereof;

FIG. 4 is a rear side elevational view thereof;

FIG. 5 is a front side elevation view thereof;

FIG. 6 is a top plan view thereof;

FIG. 7 is a bottom plan view thereof;

FIG. 8 is a second perspective view thereof; and,

FIG. 9 is a third perspective view thereof.

The broken lines in the figures depict portions of the article which form no part of the claimed design.
